RING FORMING METHOD AND APPARATUS

George R. Squibb, Birmingham, Mich., assignor to General Motors Corporation, Detroit, Mich., a corporation of Delaware

Application June 9, 1951, Serial No. 230,761

3 Claims. (Cl. 29—156.6)

This invention relates to a method of and an apparatus for making split rings for use as piston rings in the cylinders of internal combustion engines and for other purposes.

An object of the invention is to reduce the time, the number of operations, and the equipment and labor which heretofore have been required in the making of piston rings from continuous round steel wire.

Another object of the invention is to provide a method of and an apparatus for more economically forming, cutting off, and normalizing the internal stresses resulting from the forming of split rings which thereafter may be economically finished to provide piston rings for the cylinders of internal combustion engines and for other purposes.

Another object of the invention is to provide normalized split rings made from continuous steel wire, and having an external configuration on each ring which is only slightly larger than the ring after being finished by honing or grinding the external surface thereof.

Another object of the invention is economically to employ preformed steel wire to form normalized split rings having an increasing curvature from the middle of each ring toward the ends thereof. Such rings may be made to exert substantially equal resilient forces in all directions when contracted within a circular finishing tool and when finished, may be made to exert substantially equal resilient forces in all directions around the interior of a cylinder in which the ring may be employed as a piston ring or for other purposes.

Another object of the invention is to reduce the time and the expense which heretofore has been required for heat treating piston rings to normalize the internal stresses therein. Such reduction in time and expense may be secured by forming the rings in the configuration in which the rings are to be rigidly held in the heat treating fixture employed.

It is proposed to employ a continuous length of preformed steel wire to form split rings that increase in curvature from the middle toward the opposite ends of each ring. The curvature proposed is such that the rings will exert substantially uniform radial pressure against the interior surface of a cylindrical finishing tool which may be employed in later operations for grinding or honing the exterior surfaces of the rings. It is also proposed to form the rings to such configuration in order that the rearrangement of the molecular structure of the steel, which takes place during the heat treating operation, will be only the necessary rearrangement of molecules required to relieve the internal stresses caused by bending the wire to the ultimate configuration desired. It will not be necessary to relieve the stresses which heretofore have resulted from forming the rings to the ultimate configuration referred to, in the heat treating apparatus in which such rings heretofore also have been formed in the desired ultimate configuration. It is therefore proposed to form split rings for making piston rings in an apparatus for bending and cutting off wire, and then to secure the rings

2

in heat treating fixture in the form in which they were bent by the bending apparatus, for normalizing the internal stresses resulting from bending the wire.

For a better understanding of the invention, reference may now be had to the accompanying drawing forming a part of this specification, in which:

Figure 1 is a fragmentary plan view of an apparatus for bending and cutting off successive lengths of steel wire, according to the principles of the invention.

Figure 2 is a fragmentary vertical sectional view of the apparatus shown by Figure 1. Figure 2 particularly illustrates the wire holding, ring forming and cut-off mechanisms employed in the apparatus disclosed by Figure 1 and is taken substantially in the plane of line 2—2 on Figure 1.

Figure 3 is a transverse sectional view through a part of the apparatus disclosed by Figure 2, as the structure would appear substantially in the plane of line 3—3 on Figure 2.

Figure 4 is a view diagrammatically illustrating a heat treating furnace and fixture employed in practicing the invention.

Figure 5 is another transverse sectional view of the apparatus as the latter would appear substantially in the plane of line 5—5 on Figure 1, looking in the direction of the arrows thereon. Figure 5 particularly illustrates the mechanism for holding the wire while a previously formed ring is cut off.

Figure 6 is a fragmentary horizontal sectional view of the wire holding mechanism illustrated by Figure 5 and taken substantially in the plane of line 6—6 on Figure 5.

Figure 7 is a diagrammatical illustration of the method of and apparatus for bending a wire to form a split ring in the ultimate configuration desired.

The apparatus disclosed by Figure 1 comprises a machine frame 10 having bearings in which a plurality of shafts indicated at 11, 12, and 13 employed in operating the apparatus, are journaled. The shafts 11, 12, and 13 may be connected to one another by gears, not shown, and may be driven simultaneously and at the proper relative speeds by a single motor or other suitable means, not shown.

The principal mechanical elements of the apparatus disclosed by Figure 1 comprise an intermittent wire feeding mechanism 14, a wire holding mechanism 16, a wire bending mechanism 17 and a ring cut-off mechanism 18.

The intermittent wire feeding mechanism 14 is similar to that shown by Borton Patent 1,959,853, dated May 22, 1934. The wire feeding mechanism 14 comprises a clamping head 19 which is mounted on parallel rails 21 having the opposite ends thereof secured in transverse frame members 22 and 23 supported by the frame 10 of the machine. The head 19 carries a block 24 at one side thereof through an opening in which projects a continuous high carbon or other suitable steel wire 26 comprising the stock from which the rings made by the machine are formed. The head 19 comprises an internally disposed eccentric member having a part which projects into the block 24 to engage and clamp the wire 26 during the movement of the head into the advanced position shown by Figure 1. The eccentric part referred to releases the wire when the head is retracted from the position shown. The head 19 is advanced into and retracted from the position shown in Figure 1 by a link 27 which is pivotally secured at one end to a lug 28 projecting rearwardly from the head 19. The opposite end of the link 27 is likewise pivotally secured to the upper end of a lever 29 having an intermediate portion pivotally mounted upon the frame 10 and the opposite end thereof operatively associated with an eccentric 31 rigidly secured to and rotated by the shaft 12. It will be apparent that rotation of the eccentric 31 will oscillate the lever 29 in such manner

as to impart reciprocating movement to the head 19 through the link 27. The mechanism for reciprocating the head 19 upon the rails 21 is adjustable throughout any desired length of stroke and the length of stroke of the head determines the length by which the wire 26 will be advanced upon each reciprocating movement of the head.

The wire 26 is advanced toward the wire clamping mechanism 16 through a tube 32 having the opposite ends thereof secured to the transverse support 23 and a transverse support 33 which projects from the frame member 10 in spaced relation to and beyond the support 23.

The clamping mechanism 16 comprises a guide block 34 secured by screws 36 to a guide block support 37. The block 34 and the support 37 are rigidly secured in a transversely disposed opening formed across the support 33, by two of a number of screws 38 which project through openings formed in a support 37 between the upper to the lower parts thereof. The block 34 has an opening formed therein adapted to fit the wire 26 and through which the wire 26 projects and is guided in its intermittent movement toward the ring forming mechanism 17. The block 34 also is formed in such a way as to provide a transversely disposed slot 39 which projects across the block in such manner as to intersect the opening in which the wire 26 is slidably disposed. Projecting into the slot 39 in such position as to engage an adjacent surface of the wire 26, is the wire engaging end of a clamping die indicated at 41. The clamping die 41 has the opposite end thereof disposed in engagement with a tapering supporting block 42 disposed within sloping recess 43 which is formed in the end of a reciprocating actuating member indicated at 44. The block 42 is adjustably positioned with respect to the member 44 by a screw 40 which is threaded into the member 44 and which receives a nut 45 for use in securing the block 42 in the desired position. The clamping die 41 is secured in the recess 43 and against the block 42 by a screw 35 which projects through an elongated opening in the die 41 and is engaged in a threaded opening formed in the actuating member 44. The actuating member 44 is slidably disposed in a guideway formed in the support 33 in transverse relation to the path of movement of the wire 26 through the guide opening formed in the block 34. The actuating member 44 is moved inwardly to clamp the wire 26 between the die 41 and the block 39 by a lever 46 which is mounted upon a pin 47 for pivotal movement with respect to the support 33. The opposite ends of the pin 47 are rigidly secured between lugs 48 projecting from the support 33 and between which the end of the lever 36 is slidably disposed. The actuating member 44 is moved inwardly by a link 51 having semispherical bearing surfaces formed at opposite ends thereof which project into semispherical bearing openings formed in the adjacent end of the actuating member 44 and the adjacent surface of the lever 46. The actuating member 44 tends to be urged into its retracted position and to follow the operation of the lever 46 by a spring 52 which is secured in an opening formed in the support 33 in parallel relation to the opening receiving the actuating member 44. One end of the spring 52 is supported by the support 33 whereas the other end of the spring engages a block 53 secured to the end of actuating member 44 by a screw indicated at 54. The block 53 is mounted in a transversely disposed opening formed in the support 33 in such a way as to provide clearance for the movement of the block 53 with the actuating member 44 and between the support 33 and a stop member 56. The stop member 56 is secured in a recess formed in the end wall of the support 33 by a screw indicated at 57.

The lever 46 is provided at the end thereof opposite the pin 47 with a roller follower member 58. The follower member is rotatably supported on a pin 59 secured between a pair of lugs 61 formed at the end of the lever 46. The follower 58 is adapted to engage a cam 62 rigidly secured on the shaft 11 in opposed relation to the plane of movement of the lever 46.

It will be apparent that rotation of the cam 62 by the shaft 11 will operate the lever 46 to move the actuating member 44 toward the wire 26. Also, the cam 62 and the eccentric 31 employed for operating the clamping head 19 are so timed with respect to one another that the die 41 will be actuated to clamp the wire 26 with respect to the guideway formed in the block 39 after the clamping head 19 has advanced a sufficient length of the wire 26 to form a single piston ring. The die 41 holds the wire 26 rigidly with respect to the block 39 during the entire retracting movement of the clamping head 19 and is actuated by the cam 62 to release the wire 26 within the block 39 when the clamping head 19 clamps the wire 26 within the block 24 at the beginning of the succeeding advancing movement of the head 19. During such advancing movement a new length of the wire 26 is advanced through the guideway formed in the block 39 to provide material for forming a succeeding piston ring.

The succeeding lengths of the wire 26 are formed by the ring forming mechanism in such way as to provide split piston rings or split piston ring blanks or stock as indicated by the numeral 63. The ring forming mechanism 17 is actuated by a rack 64, one end of which is secured rigidly to and movable by the reciprocable clamping head 19. The opposite end of the rack 64 is slidably disposed in a guideway 66 which extends along one side of a support 67 forming the body on which the mechanical elements of the ring forming mechanism 17 are mounted. The support 67 is secured rigidly to the frame 10 in the proper relation to the other mechanical elements of the ring forming apparatus. Within the support 67 the teeth of the rack 64 engage the teeth of a pinion 68 which is formed on the hub or sleeve end of a driving element 69 of an overrunning clutch 71. The overrunning clutch 71 is similar to that shown by the patent to De Lavaud 1,542,040, June 16, 1925. The inner driven element 72 of the overrunning clutch 71 is secured by a key 73 to an enlarged concentric part 74 formed intermediate the ends of a driving shaft 76 for the operating elements of the ring forming mechanism 17. A plurality of cams 77 are disposed between the interior and exterior surfaces of the members 69 and 72, respectively, for driving the shaft 76 in one direction when the rack 64 is moved inwardly with respect to the support 67 by the advancing movement of the clamping head 19. Movement of the rack 64 outwardly with respect to the support 67 by the retracting movement of the clamping head 19 will slightly rotate the cam members 77 to release the driven member 72 from the driving member 69 of the clutch 71 to avoid rotation of the shaft 76 in the opposite direction.

In order to insure the instantaneous release of the cams 77 upon the advancing movement of the rack 64 with respect to the support 67, the end of the shaft 76 beyond the clutch 71 is provided with a friction brake indicated generally by the numeral 78. The shaft 76 is rotatably supported between the overrunning clutch 71 and the brake 78 within a bushing 79 that is secured in a cylindrical opening formed in an end wall of a housing member 81 which surrounds the overrunning clutch 71 and which is secured to a side wall portion of the support 67 by screws or other suitable means not shown. The brake 78 comprises a collar 82 which is rigidly secured to the end of the shaft 76 by a pin 83. A brake arm 84 has a split ring 86 formed at one end thereof which is adapted to be expanded or contracted with respect to the collar 82 by the operation of a screw 87 extending through a pair of lugs 88 projecting laterally from the ends of the split ring 86. A brake band 89 is operatively disposed between the exterior surface of the collar 82 and the interior surface of the split ring 86 for the purpose of frictionally opposing the movement of the collar 82 with respect to the arm 84. The opposite end of the brake arm 84 is secured rigidly with respect to a boss 91 which projects outwardly from

an upper portion of the housing 31. A screw 92 projecting through an opening in the end of the arm 34 secures the arm to the boss 91.

The end of the shaft 76 beyond the pinion 68 is rotatably supported in a bushing 93 which is rigidly secured in a cylindrical opening formed in the front side of the support 67. Between the bushing 93 and the pinion 68 is a driving pinion 94 which is keyed to the shaft 76 as is indicated at 96. The pinion 96 is adapted to engage and to drive a spaced pair of pinions 97 which are secured within the support 67 on the inner ends of a spaced pair of shafts indicated at 98. The shafts 98 are rotatably supported within the support 67 by bushings 99 which are secured in cylindrical openings formed within the front wall 101 of the support 67. The pinions 97 are secured upon the shafts 98 by keys not shown, and are secured against axial movement upon the reduced ends of the shafts 98 by screws and washers indicated at 102 and 103 respectively.

Disposed on the front wall 101 of the support 67 is a plurality of bending rollers indicated generally at 104. The bending rollers 104 comprise a spaced pair of supporting rollers 106 and 107 and a fulcrum roller indicated at 108. The supporting rollers 106 and 107 are disposed in spaced relation to one another and are secured rigidly upon the ends of the spaced and parallel shafts 98 by nuts 109 secured against washers 111 upon the threaded and reduced ends 112 of the shafts 98. The fulcrum roller 108 is rotatably secured on the end of a stud 113 having an annular shoulder 114 and a threaded reduced end 116 which are rigidly secured in suitable openings formed in a slide member indicated at 117. The slide member 117 is slidably disposed in a guideway 118 formed within the front wall 101 of the support 67. The guideway 118 and the slide member 117 contained therein project across the space between the rollers 106 and 107 in such manner as to be perpendicular to a plane intersecting axes of the two rollers and midway between the axes of the two rollers.

It will be apparent that movement of the guide member 117 within the guideway 118 will move the roller 108 farther within or away from the space between the supporting rollers 106 and 107. The rollers 106 and 107 are formed in such a way as to provide annular grooves 119 in the peripheral surfaces thereof and adjacent the outer extremities of the rollers. The grooves 119 are only slightly greater in width than the width of the wire 26 from which the rings 63 are formed, and are adapted to receive the wire 26 as the wire 26 is projected between the rollers 106 and 107 and the roller 108.

It will be apparent that the rack 64 will be actuated upon the advancing movement of the clamping head 19 to rotate the rollers 106 and 107 in a counterclockwise direction as the rollers appear in Figure 2. The rollers 106 and 107 therefore will tend frictionally to drive the wire 26 over the roller 108 when the wire is advanced by the operation of the intermittent feeding mechanism indicated at 14. Assuming that the roller 108 is adjusted to bend the section of wire supported between the rollers 106 and 107, it will be apparent that the movement of the wire 26 through the bending rollers 104 in response to the operation of the wire feeding mechanism 14 will tend continuously to bend the wire 26 while the wire is intermittently advanced.

Beyond the rollers 106 and 107 is a guide roller 121 which is adapted to guide and position the rings 63 in the region between the forming rollers 104 and the cut-off mechanism 18. The roller 121 is rotatably supported by a pin 122 secured in the bifurcated end of a bracket 123. The bracket 123 is adjustably secured upon the front wall 101 of the frame or support 67 by a screw 124 which projects through an elongated slot 126 with which the bracket 123 is provided. It will be apparent that proper adjustment of the bracket 123 will cause the roller

121 to follow the exterior surfaces of the rings 63 as the latter are being formed by the forming rollers 104.

In order to insure that the wire 26 may be started through the forming rollers 104 without too much difficulty, there is provided between the supporting rollers 106 and 107 a stop member 127 having an angularly formed end indicated at 128. It will be apparent that the end of the wire 26 will engage the end 128 when a new supply of wire is being started through the machine and that the stop member 127 will tend to bend the end of the wire in such manner as to tend to direct the wire beneath the roller 106 and within the groove 119 formed in the roller 106. The stop member 127 may be adjusted as desired by operation of a lever 129 projecting from a shaft 131. The shaft 131 has an eccentric 132 which is disposed within a transverse slot 133 formed in the end of the stop member 127 remote from the rollers 106 and 107. Shaft 131 is rotatably secured in concentric bearing openings formed in a block 134 which is secured to the front wall 101 of the support 67 by screws indicated at 136. The member 127 is slidably disposed in a transversely disposed slot 137 which is formed in the block 134 in such a way as to intersect the shaft 131. The shaft 131 is secured in the block 134 by a snap ring indicated at 138. It will be apparent that rotation of the shaft 131 by the lever 129 will move the stop member 127 with respect to the rollers 106 and 107 by operation of the eccentric 132.

It will be apparent that movement of the fulcrum roller 108 toward and away from the space between the supporting rollers 106 and 107 will vary the curvature of the section of wire supported between the supporting rollers 106 and 107 as the wire 26 is formed to provide the ring 63. As the roller 108 moves toward the space between the rollers 106 and 107, the curvature of the wire section being formed will be increased and as the roller 108 moves away from the space between the rollers 106 and 107 the curvature of the wire section being formed will be decreased. It is now proposed to provide means for varying the curvature of a length of the wire 26 required to make one of the rings 63. It is proposed to vary the curvature of such length of wire in such manner that the curvature of the length of wire will increase from the middle of the length toward the opposite ends thereof. The curvature of ring 63 formed in this manner will increase from the middle of the ring toward the opposite ends thereof. To so vary the curvature of the ring 63 it is proposed progressively to move the fulcrum roller 108 toward and away from the supporting rollers 106 and 107. To so move the roller 108 the slide 117 is adapted to be moved in the guideway 118 by an adjusting mechanism indicated generally at 141. The adjusting mechanism 141 comprises a rod 142 having one end thereof secured in a threaded opening formed in the adjacent end of the slide member 117. The opposite end of the rod 142 supports a split circular ring nut 143 which may be rigidly secured upon the threaded end of the rod 142 by tightening a screw 145 disposed in a threaded opening intersecting the split end of the nut 143. The screw 145 may be loosened for adjustably positioning the nut 143 upon the end of the rod 142 by turning the nut 143 with a spanner wrench adapted to engage radial openings 144 formed in the periphery of the nut. The nut 143 is adapted to be engaged by the flange end 146 of a sleeve 147 which surrounds the rod 142 and extends to within a short distance of the end of the slide member 117. The opposite end of the sleeve 147 is threaded in such manner as to receive and to have secured thereon a threaded collar indicated at 148. The sleeve 147 is slidably disposed in a bearing 149 formed in a cylindrical support 151 which is formed as an integral part of a supporting bracket indicated at 152. The supporting bracket 152 is secured rigidly by screws 150 to an angularly disposed upper wall 153 which is formed

on the support 67 in perpendicular relation to the path of movement of the slide member 117. A spring 154 is confined within an annular opening 156 formed in the support 151 and between the shoulder formed by the bearing 149 and the ring 148. It will be apparent that the spring 154 will tend resiliently to move the rod 142 and the slide member 117 in such manner as to move the fulcrum roller 108 away from the supporting rollers 106 and 107. Such movement of the roller 108 by the spring 154 is opposed by a cam operated lever indicated at 157. The lever 157 is mounted intermediate the ends thereof upon a pin 158 which is secured between a pair of spaced supports 159 the lower ends of which are formed integrally with respect to an integral wall 161 forming a part of the bracket 152.

The actuating end of the lever 157 is formed in such a way as to provide a yoke 162, the ends of which project on opposite sides of a part of the sleeve 147 below the flange 146. The upper ends of the yoke 162 have semi-cylindrical bearings 163 formed thereon which are adapted to project within semi-cylindrical openings formed in the lower surface of a bearing ring 160. This ring 160 is slidably disposed about the sleeve 147 adjacent the flange 146.

It will be apparent that movement of the lever 157 to elevate the sleeve 147 will tend to move the fulcrum roller 108 toward the space between the supporting rollers 106 and 107 to increase the curvature of the section of wire being supported between the rollers 106 and 107.

The lever 157 may be moved in such manner as to increase the curvature of the wire being formed by the bending rollers 104 by a cam 164 which is secured by screws 166 upon the rotatably mounted shaft 13. The exterior surface of the cam 164 is adapted to engage a roller follower 167 which is secured by a pin 168 in the bifurcated end 169 of the lever 157. For convenience in maintenance and assembly, the cam 164 may be formed in two parts indicated at 171 and 172. While it will be apparent that the exterior surface of the cam 164 may be formed in such a way as to provide a ring 63 of any desired curvature, it is considered desirable to form the cam 164 in such manner that the radii of curvature in opposite directions upon the surface of the cam will increase at a relatively uniform rate from a minimum to a maximum radius of curvature at diametrically opposed points on the surface of the cam 164. The exterior surface of the cam 164, as illustrated by Figure 2, is, accordingly, made in such manner that the radii of curvature of the surface of the part 171 of the cam 164 increases at a relatively uniform rate from the middle toward the opposite ends of the surface and the exterior surface of the part 172 of the cam 164 increases from the ends toward the middle thereof at a similar relatively uniform rate.

Referring to all of the figures of the drawing and particularly to Figure 7, it will be noted that the apparatus is shown with all of the mechanical elements thereof in the positions they assume after a ring 63 has been formed from the wire 26 and just prior to the time when the ring 63 is cut off from the wire 26 by operation of the cut-off mechanism indicated at 18. The fact will be observed that in order to bend the wire 26 into the form of a ring 63 it is necessary to bend the section of wire supported by the supporting rollers 106 and 107 to a curvature considerably exceeding the curvature which the corresponding part of the ring 63 will assume after it has traversed the bending rollers 104. When such fact is considered, it will be apparent that the ring formed by the bending rollers will tend to assume a position somewhat to the right hand side of and above the axis of curvature of the section of the wire supported by the rollers 106 and 107. To prevent the axis of curvature of the ring 63 from assuming such position and to insure that the ring will not be distorted by again improperly

contacting the rollers 106 and 107 after the ring is formed, it has been found to be desirable to overbend a small section of the wire 26 at the junction of each length of the wire 26 used in forming the rings 63. In order to so overbend the wire 26 in such regions and for such purposes, it has been found desirable to provide the cam 164 with a hump 173, the surfaces forming the hump being of rapidly increasing and decreasing radii of curvature as compared to the moderately increasing and decreasing radii of curvature of the surfaces of the section 172 of the cam 164 on opposite sides of the hump 173. It will be apparent that the hump 173 will suddenly greatly accelerate the inward and outward movement of the roller 108 with respect to the rollers 106 and 107 at the junctions between the lengths of the wire 26 employed in forming successive rings 63. In terms of the engagement of the surfaces of the cam 164 with the follower 167 of the lever 157, the hump 173 will engage the follower 167 at the time when the surface of the cam 164 engaging the follower 167 changes from an increasing to a decreasing radii of curvature. It will be apparent that the abrupt change in the movement of the lever 157 by the hump 173 will tend abruptly to bend the wire 26 at the junctions between the lengths of the wire 26 employed in forming successive piston rings indicated at 63.

The entire mechanism including the cam 164 is timed in such manner that a ring 63 will be formed and the wire feeding mechanism 14 will be stopped when the junctions between successive lengths of the wire 26 are diametrically opposed to the ring forming rollers 104 and in the position of one of the junctions indicated at 174 which appears between the dot-and-dash lines intersecting the wire 26 approximately at right angles in the diagrammatic illustration disclosed in Figure 7.

In order to separate the successive rings 63 from the wire 26 it is proposed to cut off the rings 63 by cutting out of the wire 26 successive blanks indicated at 174, which represent sections of the wire which traverse the bending rollers 104 at the junctions of the successive lengths of wire employed in forming the rings 63.

The cut-off mechanism 18 which is employed for such purposes comprises a block 176 which is secured to the support 67 in such manner that the front surface of the block is in the plane of the inwardly disposed edge surfaces of the grooves 119 which are formed in the supporting rollers 106 and 107 and through which the wire 26 passes during the bending of the wire to form rings such as that indicated at 63. Assuming the bending rollers 104 to be properly aligned and the wire 26 to be straight, it will be apparent that the wire 26 bent by the bending rollers 104 will traverse the front surface of the block 176 with the adjacent surface of the wire in sliding engagement with the block 176. A part of the block 176 is provided with an opening for receiving a die 177, the latter having an opening 178 formed therein for receiving the cutting end 179 of a punch indicated at 181. The cutting end of the punch 179 which corresponds to the shape of the opening 178 will be seen in Figure 2 to comprise a geometrical figure similar to an isosceles trapezoid in which the non-parallel sides of a figure are indicated in dotted lines in Figure 2. The non-parallel sides of the cutting end 179 of the punch 181 are formed in such a way as to be disposed approximately normally to the ends of section 174 of the wire 26 so that the ends of the ring 63 will be formed with surfaces that close at the outer periphery thereof when the ring is contracted within a cylinder in which such rings are employed.

The punch 181 is slidably mounted in an opening formed in one of a plurality of sections 182, 183 and 184 of a tool supporting head indicated at 186. The head 186 is secured to the frame member 10 by screws indicated at 187. The sections of the head 186 indicated at 182, 183 and 184 are likewise secured together by screws indicated at 188. Slidably disposed in an opening formed in the sections 183 and 184 of the head 186 and

at one side of the opening receiving the punch 181 is a work holding member indicated at 189. The member 189 is disposed in spaced and parallel relation to the punch 181 and circumferentially beyond the blank 174 with reference to the formation of the wire 26 into one of the rings 63. The work holder 189 has an end surface formed in parallel relation to the front face of the block 176, the end surface referred to being normally spaced from the block 176 so that the wire 26 can extend between the work holder 189 and the block 176 during the formation of one of the rings 63. The punch 181 and the work holder 189 are adapted to be actuated by a cam mounted upon the hub of a flywheel 190 which is rigidly secured upon the shaft 11. The cam projects within a cam housing indicated at 191 which is secured rigidly to the frame 10. The cam referred to is adapted to operate a reciprocating tool actuating member 192 which is slidably mounted within the housing 191 and which extends from the housing 191 into engagement with the punch 181. The work holder 189 is spring actuated by the tool actuating member 192 so that the spring will be compressed after the work holder 189 clamps the rings 63 successively against the block 176 and while the punch 181 is being projected into the dot-and-dash line position within the die 177. The dot-and-dash line position of the punch 181 referred to is illustrated by Figure 3. During the movement of the punch 181 from the full line to the dot-and-dash line positions illustrated by Figure 3, the blank 174 is cut from the junction between two lengths of the wire 26 which are operated upon by the forming rollers 104 to provide one of the rings 63. The punch 181 projects the blank 174 through the die 177 and from the machine through successive openings 193 and 194 formed, respectively, in the block 176 and the adjacent part of a support 67.

It will be apparent from Figures 2, 3 and 7 that a ring 63 having a gap diametrically opposed to the forming rollers 104, cannot be formed without overlapping the adjacent convolutions of the wire 26 in the vicinity of the forming rollers 104. Since such overlapping of convolutions will tend to cause the rings 63 to be distorted out of the planes which it is desired to have the rings assume after the formation thereof, it is proposed to so modify the mechanism as to prebend the wire 26 and to so modify the rollers 106 and 107 with respect to the ring engaging surface of the block 176 that the rings 63 will be finally formed in the planular configuration desired.

To accomplish such end it is proposed positively to guide the rings 63 after the formation thereof by the forming rollers 104 by employing grooves 196 which are formed in the ends of the supporting rollers 106 and 107 in spaced relation to the grooves 119 formed therein. The rollers 106 and 107 also are chamfered at 197 around the peripheral surfaces thereof between the grooves 119 and 196. This is done for the purpose of directing the ends of the successive rings 63 into the guiding grooves 196 after the wire 26 has been bent by the bending rollers 104 while traversing the grooves 119 and the exterior surface of the roller 108. It will be noted from Figure 3 that the roller 108 does not project outwardly as far as the grooves 196 so that the rings 63 are not engaged by the bending rollers 104 after the wire 26 is originally formed by bending the wire within the grooves 119 and between the fulcrum roller 108 and the supporting rollers 106 and 107. Assuming that the wire 26 employed in forming succeeding rings 63 must traverse and be guided and confined within the grooves 119 and 196, then it will be apparent that the front surface of the block 176 should be positioned in a plane which will cause the least possible distortion of the loop of the wire 26 that projects between the end surfaces of the punch 181 and the work holder 189 and the front surface of the block 176. It will be apparent from Figure 3 that sufficient space is provided between the adjacent surfaces of the head 186 and the block 176 that the leading end of the ring 63 can be dis-

posed in such space and without excessively distorting the wire employed in forming the ring 63. It will also be apparent from Figure 7 that the leading end of the wire employed in forming the ring 63 will stop approximately at the adjacent edge of the cutting end 179 of the punch 181, when the advancement of the wire 26 is stopped between the formation of successive rings 63.

Since the grooves 196 and the ring engaging surface of the block 176 may slightly distort successive rings 63 being formed by the ring forming rollers 104, it is proposed to oppositely distort the wire 26 prior to the entrance of the wire into the groove 119 in the guiding roller 107 and between the guiding roller 107 and the opening in the block 39 from which the wire 26 emerges from the work holding or clamping mechanism indicated at 16. For so distorting the wire 26 it is proposed to employ a roller 198 having a groove 199 formed in the peripheral surface thereof for receiving the wire 26. The roller 198 is rotatably supported by a pin 201 having the ends thereof secured in a block 202 having a groove formed therein for receiving the roller 198 and across which the pin 201 extends. The block 202 is adjustably mounted in such manner as to be axially movable with respect to the roller 198, upon a support 203 which is secured to the support 67 by screws indicated at 204. The position of the block 202 may be adjusted by a lever 206 adapted to control the operation of a screw mechanism by which the roller 198 may be moved axially with respect to the wire 26. It will be apparent that axial movement of the roller 198 in the proper direction with respect to the roller 107 and the opening in the block 39 will progressively bend the wire 26 prior to its entrance into the bending rollers 104 and in such direction that the bending of the wire in spiral formation resulting from the formation of the successive rings 63 will tend merely to straighten the wire forming the ring 63 by bending the wire in a direction opposed to the preliminary bending established by the roller 198.

It will be apparent that the surfaces of progressively increasing and decreasing curvature formed on the cam 164 on opposite sides of the hump 173 will first progressively move the fulcrum roller 108 outwardly with respect to the supporting rollers 106 and 107 as the leading end of a length of wire required for the formation of one of the rings 63 progressively moves through the forming rollers 107 from the leading end to the middle of such length of wire. Thereafter such surfaces on the cam 164 will progressively move the fulcrum roller 108 inwardly with respect to the supporting rollers 106 and 107 as the length of wire progresses through the bending rollers 104 from the middle toward the following end of such length of wire. Such movement of the fulcrum roller 108 will result in the formation of a ring 63 in which the curvature of the length of wire forming the ring will increase from the middle of the ring toward the opposite ends of the ring.

It has been found that when such a ring is confined within a cylinder in which the ring is designed to be employed, it can be made to exert practically uniform pressure against the interior surface of the cylinder and throughout the entire length of the ring.

It will be apparent that any desired modification of such uniform pressure exerted by one of the rings can be obtained by modifying the surface of the cam 164 to vary the bending of the ring to secure the pressure pattern desired. It has also been learned that for all practical purposes all of the variation in radius of curvature of the cam 164 may be applied to the part 172 of the cam where the surface of greatest radius of curvature is found. This may be done for the reason that the variation in radius of curvature required throughout the entire surface of the cam 164 excluding the hump 173 is so small, amounting to only a few thousandths of an inch in the entire cam, that a constant radius of curvature throughout the

entire extent of the surface of the part 171 of the cam will not noticeably affect the shape of the ring 63 when completed.

The rings 63 may be successively removed from the grooves 196 in the bending or supporting rollers 106 and 107 after the rings have been released by operation of the cut-off mechanism 18.

When the rings have been so removed from the machine, they may be heat formed, set, tempered or normalized in a heat treating furnace by the employment of a heat treating fixture such as that illustrated by Figure 4. The heat treating apparatus shown by Figure 4 comprises a heat treating furnace 207 having a series of hooks 208 projecting from the upper wall thereof, on which a plurality of heat treating fixtures such as that indicated at 209 may be hung. The furnace may be heated in any suitable manner as by the employment of electrical heating elements indicated at 211. The fixture 209 comprises a ring supporting mandrel 212 through which a rod 213 is adapted to project between end plates indicated at 214 and 216. The rod 213 is rigidly secured with respect to end plate 214 and from which the fixture 209 is adapted to be hung by an eye 217 forming the head of the bolt 213. Beyond the end plate 216 the bolt 213 is threaded to receive a nut 218 by the tightening of which the distance between the plates 214 and 216 may be varied. A stack 219 of the rings 63 is adapted to be disposed on the exterior surface of the mandrel 212 with the gaps in the rings of the stack in alignment with one another. The rings in the stack 219 may be clamped in rigid relation to one another upon the mandrel 212 by clamping rings 221 which are secured to the inner surfaces of the end plates 214 and 216 in such positions as to be directly opposite the ends of the ring stack 219 disposed upon the mandrel 212. The thickness of the rings 221 is somewhat less than the thickness of the rings 63 in the stack 219 and the diameter of the rings is sufficient to receive the ends of the mandrel 212 internally thereof. The rings in the stack 219 may be clamped against the exterior surface of the mandrel 212 by a plurality of clamping bars 222 which are adapted to be disposed outside of the ring stack 219, to extend from one end to another of the ring stack and in parallel relation to the axis of the mandrel 212. The bars 222 may be clamped against the ring stack 219 by screws 223 which project through a plurality of rings 224 that surround the bars 222 and that are spaced from one another throughout the length of the bars 222. The rings 224 are spaced with respect to one another so as to be held in proper relation to the bars 222 by frame members indicated at 226.

The external configuration of the mandrel 212 is such that the rings 63 may be clamped by the bars 222 to the exterior surface thereof practically without distorting the rings from the configuration in which the rings are formed by the ring forming apparatus previously disclosed. The force exerted by the bars 222 upon the exterior surface of the ring stack 219 therefore will be only the minimum force required to rigidly clamp the rings against the exterior surface of the mandrel 212 to prevent distortion of the rings during the process of heat treating the rings in the furnace 207. Due to the fact that the individual rings in the stack 219 are not appreciably distorted by clamping the rings to the exterior surface of the mandrel 212 it will be apparent that the heat treatment required in the furnace 206 will be only the minimum amount of heat treatment required to release the internal stresses in the rings caused by the bending of the wire 26 in the ring bending apparatus referred to. Since the time required for normalizing the internal stresses in the rings is proportional to the extent to which the molecules of the material must be rearranged within the rings, it will be apparent that a shorter time will be required to normalize the internal stresses in the rings if the rings are formed by the ring forming apparatus in a configuration

similar to the configuration of the exterior surface of the mandrel 212 than if the rings are formed according to some other configuration and are bent into the configuration of the exterior surface of the mandrel 212 by operation of the clamping bars 222.

It will be apparent that the rings in the stack 219 will be positioned upon the mandrel 212 with the surface of least curvature on the mandrel 212 opposite the middle portion of the rings in the ring stack 219 and with the surface of greatest curvature on the mandrel in opposed relation to the ends of the rings on opposite sides of the aligned gaps therein. When the rings are so clamped within the fixture 209, the fixture may be suspended in the heat treating furnace 207 by hanging the eye 217 upon one of the hooks 208.

It has been found that a temperature of about 1000° is a suitable temperature for normalizing stacks of rings made from steel wire so formed and confined within fixtures such as that indicated at 209 and to be heat treated in a heat treating furnace such as that indicated at 207.

I claim:

1. A method of making piston rings which comprises projecting a plurality of successive lengths of a continuous wire between bending rollers for continuously bending said wire in one direction, moving the fulcrum roller away from the supporting rollers of said bending rollers intermediate the junctions between said successive lengths and toward said supporting rollers at said junctions between said lengths and during the formation of one ring from each of said lengths, abruptly changing the movement of said supporting roller toward and away from said supporting rollers in the immediate vicinity of each of said successive junctions to accentuate the curvature of said lengths adjacent said junctions, and thereafter cutting out blanks from said wire at said junctions to include said accentuated curvature of said wire formed at said junctions.

2. A ring forming machine comprising a plurality of bending rollers for continuously bending successive lengths of a continuous wire in one direction and at the same increasing and decreasing curvature for each of said lengths, a cam for relatively moving said bending rollers for increasing and decreasing said curvature, means for cutting a blank from said wire at the junction between the portions of greatest curvature in successive lengths of said wire and drive means for driving said cam and said bending rollers in timed relation, said timed relation being such that said cam rotates one revolution as said bending rollers bend one convolution in each length of said wire.

3. A ring forming machine comprising a plurality of forming rollers for successively bending continuous lengths of wire in one direction, a cam for relatively moving said bending rollers for varying the curvature of said wire from one end to another of said lengths, cut-off means having the opposed cutting edges thereof disposed normally with respect to the curvature of said wire for cutting a blank from said wire at the junctions between said successive lengths of wire and drive means for driving said cam and said bending rollers in timed relation, said timed relation being such that said cam rotates one revolution as said bending rollers bend one convolution in each length of said wire.
